Atty's.

UNITED STATES PATENT OFFICE.

CHARLES M. HELLER, OF CHICAGO, ILLINOIS, ASSIGNOR OF ONE-HALF TO HIMSELF
AND ONE-HALF TO EDWIN A. KANST, OF CHICAGO, ILLINOIS.

INK BOTTLE AND STAND.

1,200,611.

Specification of Letters Patent. Patented Oct. 10, 1916.

Application filed July 15, 1915. Serial No. 40,024.

To all whom it may concern:

Be it known that I, CHARLES M. HELLER, a citizen of the United States, residing at Chicago, in the county of Cook and State 5 of Illinois, have invented certain new and useful Improvements in Ink Bottles and Stands, of which the following is a specification, reference being had to the accompanying drawings.

10 My invention relates to ink-bottles and inkstands, and has primarily for its object to provide a new and improved ink-bottle in connection with a base adapted to coöperate therewith to form an inkstand of such 15 construction that the ink-bottle may conveniently be sold separately as an ordinary bottle of ink, and may conveniently be applied by the purchaser to the base so as to form therewith a cheap and efficient ink- 20 stand.

A further object is to provide a bottle and stand of such construction that the bottle may readily be adjusted to different positions in order to provide easy access to the 25 ink as its level in the bottle is lowered; also to provide a stand adapted to coöperate with a bottle of the character described and provided with means to receive and retain any overflow that may occur from accidental 30 causes, and also to serve as a pen holder.

I accomplish these objects as illustrated in the drawings and as hereinafter described.

That which I believe to be new is set forth in the claims.

35 In the accompanying drawings, Figure 1 is a side elevation of my improved ink-bottle and stand; Fig. 2 is a vertical cross-section thereof, showing the application of a pen thereto, said section being taken on line 40 2-2 of Fig. 3; Fig. 3 is a plan view of the bottle and stand shown in the preceding figures; Fig. 4 is a view showing a modification; Figs. 5 and 6 are vertical sectional views of the upper end of the neck of the 45 bottle, showing two forms of closures that may be applied thereto; and Figs. 7, 8 and 9 are sectional views of the bottle, showing different positions to which it is turned when the level of the ink therein falls, so as to 50 make the ink readily obtainable.

Referring to the drawings, 10 indicates the stand or base, and 11 the bottle. The stand, which is preferably glass, but may be made of any other suitable material, is in the main rectangular in plan with its front 55 corners rounded as shown in Fig. 3. It is divided transversely by a partition 12 having a concave recess 13 at the center to receive the neck 14 of the bottle, as hereinafter described. At the rear side of the partition 60 12 is a compartment having a concave bottom 15, the upper surface of which is provided with a series of corrugations 16 extending transversely of the stand. These are best molded as a part of the stand. 65 Their length is preferably equal to the width of the bottle. At the opposite side of the partition 12 is a trough 17 having an inclined bottom 18 extending up to the upper front surface of the stand. 70

19 indicates the ends of the trough, which also form the sides of the stand and merge with the partition 12. They also merge with the ends 20 of the bottle receiving compartment, so that the upper edge of the stand 75 is practically all in the same horizontal plane. The sides 18 are provided with one or more alined recesses 21, which serve as a pen-rack.

The bottle 11 is illustrated as cylindrical 80 in form, and has its neck 14 disposed centrally and tangentially, as best shown in Fig. 2. The neck of the bottle is adapted to fit in the recess 13 when the bottle is in the position shown in Fig. 2, or approximates 85 that position, but the bottle may also be turned so that the neck 14 stands upright as shown in Fig. 1. At a convenient point on its outer surface, the bottle 11 is provided with a number of ribs or corrugations 90 21' adapted to engage or mesh with the corrugations 16 of the bottom 15, in the manner shown in Fig. 2. By this means the bottle is automatically held in different positions of adjustment, but may readily be 95 rocked to cause the ink to flow toward the outlet. It will be at once apparent that when the bottle is full the ink will be readily accessible when the bottle is turned to an upright position, or to the position shown in 100

Fig. 7, in which the neck is slightly inclined from the vertical. As the level of the ink recedes, the bottle may be turned to incline the neck more and more, so that even when 5 the level of the ink is very low, as shown in Fig. 2, it still flows to the outlet end of the neck and is easily within reach of the pen. As best shown in the sectional views 10 of the bottle, the neck is preferably provided with a dam 22 at the lower side of the outlet opening, the effect of which is to permit the neck of the bottle to be inclined to a greater extent without spilling ink. The outlet opening only, however, is constricted 15 in this way, and the free flow of ink in the neck adjacent to the outlet is not restricted. The outer end of the neck is preferably provided with screw-threads so that it may receive a screw-cap 23, and, if desired, a 20 washer 24 may be placed in the cap to prevent leakage when the bottle is packed for shipment. Fig. 5 shows a metal cap with a washer; while Fig. 6 shows a glass cap without a washer. Either form may be employed, the latter being more suitable for 25 use when the ink is in use, while the former is preferred for shipping purposes.

In Fig. 4 I have illustrated an arrangement in which instead of using the corrugations on the bottle and on the stand to hold 30 the bottle in its different positions, I provide the stand with a broad, flat spring 25, which embraces the central portion of the bottle, and which preferably is provided with two 35 end flanges 26 arranged parallel with each other and far enough apart so that the spring 25 fits between them. The frictional engagement between the spring and the bottle is sufficient to hold the bottle when it is 40 turned to incline the neck to a greater or less extent, but does not interfere with its ready removal or insertion.

My improved stand and bottle provide an outfit of which the base portion of the stand 45 (by which I mean the stand without the bottle) may be very cheaply manufactured and is suitable for use as a permanent piece of desk furniture. The bottle portion of the inkstand may also be very cheaply constructed. In fact, it may be manufactured 50 and sold in the same way as the ordinary bottle of ink. It may then be applied to the base portion of the inkstand just as it is when purchased, forming therewith a complete 55 inkstand. This avoids the necessity of transferring the ink from the bottle in which it is purchased to the ink container of an inkstand, as has heretofore been the practice. By my invention, therefore, the user instead 60 of buying an ink-bottle and using ink from it, with the consequent danger of upsetting the bottle and spilling the ink, may buy my improved bottle and by applying it to the base portion of the inkstand as described

will have a convenient, ornamental inkstand 65 in which the bottle cannot well be upset and the ink cannot be spilled. Furthermore, as is a matter of universal experience in using ink from a bottle, as the ink level recedes it is difficult to obtain ink without smearing 70 the pen and the fingers of the writer, whereas with my improved device, however low the level of the ink in the bottle, it is always 75 equally available for use without inserting the pen-holder itself into the neck of the bottle, and consequently there is no danger of the user soiling his fingers. A further advantage of my improved device is that it provides for the ready substitution of bottles of ink of different colors or kinds. 80

My improved device may be made of any suitable material, such as glass, tin, wood, aluminum, etc., but I prefer to make it of glass.

That which I claim as my invention, and 85 desire to secure by Letters Patent, is,—

1. An inkstand, comprising a base having a semi-cylindrical compartment to receive an ink-bottle, said compartment having corrugations, and a substantially cylindrical ink-bottle adapted to fit in said compartment 90 and having one or more corrugations coacting with the corrugations of the compartment to hold the bottle in different positions of adjustment, said bottle being free to be 95 lifted from said compartment and having a neck projecting beyond the outer surface thereof.

2. An ink-stand comprising a base having a compartment, the surface of which is circular in cross-section, an ink-bottle curved concentrically to the surface of said compartment to conform to the shape of the latter and adapted to fit snugly therein, said bottle being removably mounted in said compartment to be rocked to different positions therein and having a tangentially disposed neck projecting beyond the outer surface thereof, and coöperating means on the contacting concentric surfaces of the bottle and 110 the base for holding the bottle in different positions of adjustment.

3. An ink-stand comprising a base having a compartment, a portion at least of the upper surface of which is in the form of an arc 115 of a circle, an ink-bottle a portion at least of the surface or perimeter of which is in the form of an arc having the same radius as the arc on which the surface of said compartment is taken, said bottle being adapted 120 to fit in said compartment and to be rocked to different positions therein, said bottle having a tangentially disposed neck projecting beyond the outer surface thereof, and means between the bottle and the base for 125 holding the bottle in its different positions of adjustment.

4. As a new article of manufacture, an

inkstand comprising a substantially cylindrical ink-bottle having a neck projecting beyond the outer surface thereof, a base having a compartment to receive the ink-bottle, said compartment having means co-operating with the ink-bottle to hold it in

different positions of adjustment, a trough adjacent to said compartment, and a partition separating said compartment from said trough, said partition having a recess open 10 at the top to receive the bottle neck.

CHARLES M. HELLER.
